standard 2 has mounted thereon for rotation, a sleeve 3 carrying thereon the carrying head 5, the sleeve 3 being rotated by any suitable mechanism (not shown). The head is formed by a casting having a top plate 5^a, having two concentric annular walls 5^b and 5^c projecting downwardly from its under surface. The outer wall 5^c is near the outer edge of the plate, but such edge of the plate is interrupted by a series of arms 10 radially projecting from the plate 5^a at regular intervals therearound. These arms each comprise top and bottom flanges 7^a and 7^b connected by radial vertical webs 7^c, the inner ends of which join the exterior of the wall 5^c, and the top flanges 7^a of which form an extension of the top plate 5^a. Between each of the arms 7, the top plate is further provided with a peripheral extension 8 which, by preference, is slightly thicker than the body of the plate.

A series of radial bars 9 are mounted on the top plate above the peripheral arms formed by the parts 7^a, 7^b and 7^c, the bars having on their opposite ends the bearings 9^b and 9^c to receive radial shafts to be hereinafter described.

The head carries an air-pumping mechanism comprising a plurality of cylinders 10, arranged around the upper end of their piston-actuating shaft 11 which extends upwardly within the tubular standard 2, and is suitably driven. The upper end of the shaft 11 carries a crank arm 13 having an upwardly projecting wrist pin 13^a on the end thereof adapted to actuate the piston rods 14 of the air-pumps, which deliver air through the pipes 11^b into a reservoir formed in the head between the annular walls 5^b and 5^c.

Inasmuch as the head 5 carries a number of complete mechanisms, which are duplicates of each other, one of such units being associated with each peripheral arm formed by the parts 7^a, 7^b, and 7^c. The following description will be drawn to one such unit, it being understood that such units may be multiplied as desired.

The ends of the top and bottom flanges 7^a and 7^b of the arm are extended outwardly beyond the web 7^c thereof, and are formed in the ears 7^d, between which is mounted a spindle-carrying frame. This frame comprises a substantially triangular part which, at its base has ears 16^d formed thereon located between the ears 7^d of the arms, the upper set of ears being articulated together by a sleeve 17 to which the upper ear 16^d is keyed and which projects through a bearing in the ears 7^d, while the lower ears are articulated together by a pin 18. The sleeve 17 extends upwardly above the ears 7^d and has fast on its upper end a gear 17^a which meshes with a rack 17^b carried upon the outer end of a bar 17^c mounted for radial movement on the top plate 5^a, the inner end

of said bar having a stud roller 17^d thereon engaging a cam-way in the lower face of a plate 20 carried upon, and held against movement by the top of the standard 2 and located about the top plate 5^a. 70

It will be seen that the bar 17^c will partake of the movement of the head around the standard, and that it will in consequence thereof be given a radial movement dependent upon the shaping of the cam with which it engages, and that in such radial movement it will, through the pinion 17^a and sleeve 17 turn the carrying frame 16 upon the vertical axis formed by such sleeve and by the pin 18. The cam is so shaped that in 80 the rotation of the head, the frame 16 will, in the rotation of the head, be turned to different angular positions around its pivotal mounting on the head. Among the various movements resulting from these angular 85 movements of the frame may be the projection into and withdrawal of the spindle from the furnace, and the positioning of the horizontal pivot of the spindle (to be hereinafter described) to permit the spindle to 90 be brought into proper co-operative relation with the marverer and with the blowing and molding mechanism.

The structures above referred to are fully disclosed in my original application afore- 95 said, and need no further description herein as the same do not in themselves form the subject-matter of claims in this application.

At the apex of the carrying frame 16 is formed a bearing for the spindle-support 21, 100 such support having a trunnion 21^a which is horizontally mounted in the apex of the carrier, so that the glass-carrying spindle mounted in such support will be movable in a vertical plane. For the purpose of moving the glass-carrying spindle in a vertical plane around its trunnion mounting, a beveled gear 23 is keyed to the free end of the trunnion, and is driven through a pinion 23^a fast on the upper end of a horizontal 110 shaft 23^b contained in bearings in the frame 16. The shaft 23^b has on its inner end a beveled pinion 23^c which meshes with, and is driven by a corresponding pinion 23^d mounted on the pin 18 and fast to the gear 23^e. A 115 beveled gear 24 is mounted in the arm 7 near the bearing 7^c and has fast on its lower end a pinion 24^a meshing with a gear 23^f and has on its upper end a gear 24^b, which meshes with the outer end of a rack bar 24^c, 120 mounted for radial movement above the top plate 5, the inner end of such bar having a stud roller 24^d on the lower face thereof taking into a cam-way on the upper face of the fixed plate 20. It will be seen that 125 the bar 24^c overlies the bar 17^c which swings the frame 16, and that like the bar 17^c the bar 24^c will partake of the movement of the head around the standard, and that will in consequence thereof be given a radial 130

movement dependent upon the shape of its actuating cam, and that in such radial movement will rotate through the gear 24^b, vertical shaft 24, pinion 24^a, gears 23^f, 23^e and 23^d, horizontal shaft 23^b and gears 23^a and 23^c, the spindle support 21 around its axis as formed by its trunnion 21^a and swing the glass carried thereon in a vertical plane. The shape of such cam, is such, when the motion thereof is compounded with the relative motion of the gears 23^d and 23^e, due to any motions that may be given to the carrier 16 upon its vertical pivots, that it will effect proper motion of the spindle support 15 to lower the end of the spindle thereon into the furnace to effect a gather of glass, and will then withdraw such gather of glass and lift the spindle until the gather end thereof is above the horizontal and is in proper position to permit the marvering of the glass thereon to hold the spindle in such raised position, and will then further swing the spindle to oscillate it for elongation of the glass and will then position the spindle vertically in proper relation for blowing and molding.

Mounted within the spindle support 21 is rotatably contained the spindle stem 22, which has keyed on its upper end and above the support, a beveled gear 26 which, through the interposition of a double beveled gear ring 26^a sleeved on the trunnion 21^a is driven by a beveled pinion 26^b keyed to the outer end of sleeve 26^c surrounding the shaft 23^b and contained in the bearings in the frame 16. The opposite or inner end of the sleeve has keyed thereto a beveled gear 26^d meshing with a beveled pinion 27 on the lower end of a vertical shaft 27^a contained in the sleeve 17 of the carrier frame, the upper end of such shaft having fast thereon above the upper end of the sleeve a beveled gear 27^b driven by a beveled pinion 27^c fast on the outer end of a shaft 27^d, carried by the corresponding radial bar 9. The beveled gear 27^c on the shaft 27^d meshes with beveled gear 27^e fast to the vertical drive shaft 11 below the crank arm thereon, whereby the angular movement of such shaft in respect to the head 5 on which the horizontal shafts 27^b are carried will drive the latter and thus through the connections above described, revolve the stem 23 of the spindle around its longitudinal axis.

The stem 22 is adapted to receive the glass-working spindle 22^a, either by a permanent connection, or by a removable connection as is necessary when the gathering of the glass on the spindle is to be performed by hand. Inasmuch as in the form of mechanism shown herein the glass-working spindle 22^a is in the form of a hollow blow-pipe upon which the glass after the marvering is to be blown, I provide means for blowing such glass, such means comprising

a peripheral extension 8 of the top plate, and is provided on its under surface with an air-port 29 connected with the air chamber 15 by the passage 29^a, controlled by an air-valve 30 of proper construction. The air-valve 30^a extends through the top plate 5^a and is adapted to be displaced by a crown cam 30^b on the lower surface of a fixed plate 20, whereby on the rotation of the head 5 the valve will be actuated at proper times to place the ports 29 in connection with the air-reservoir 15.

Among the functions possessed by the movement of the frame 16 around its vertical axis and of the supports 21 around its horizontal axis, is that of positioning the blow pipes beneath the air-ports corresponding thereto, and locating the gatherers thereon at such times within a mold-cavity, as is represented in dotted lines in Figure 85, the stem 22 being hollow to connect the blow-pipe with the air-port with spindle-carrying mechanism which may be, though not necessarily, of the specific construction before described, I associate the marvering mechanism forming the subject-matter of this application, which, as shown in the accompanying drawings, in its constructional arrangement comprises a marverer 74, consisting of a hub 74^a, and a spiral marvering wall 74^b, which in longitudinal section is in the form of the frustum of a cone, the cone being open at the mouth 74^c of the spiral to permit the introduction of the gatherer into the interior thereof. The hub 74^a is mounted upon the outer end of a shaft 75 carried in bearings 76^a in a frame 76 pivoted by a horizontal stud 76^b to an extension 77, formed upon the end of the arm in which the corresponding carrying frame 16 is pivoted. A gear 76^c is fast upon the frame 75 concentric with its pivotal point, and meshes with the pinion 78^a keyed to a horizontal shaft 78 which is carried in bearings 77^b and 79 upon the extension 77 and the corresponding radial bar 9, respectively. Two gears 80 and 80^a are sleeved upon the horizontal shaft, and mesh with pinions 81 and 81^a, the former of which is formed upon the hub of the beveled pinion 27^c through which the glass carrier is rotated, while the latter is formed on the hub of a second beveled pinion 81^b, sleeved on the driving shaft 27^d and engaging and being driven by the beveled gear 27^e at a point diametrically opposite to that at which the pinion 27^c engages the gear. Thus the two gears 80 and 80^a are reversely rotated. As before stated the gears 80 and 80^a are loose upon the shaft 78 but either is adapted to be locked thereto and for this purpose the said gears have clutch teeth 80^b formed upon their opposing faces, between which faces a block 82 provided with corresponding clutch teeth is adapted to slide upon the shaft 78, being

120

125

130

feathered thereto by a pin 82^a, which also passes through a rod 83 located within the inner end of such shaft, the end of such rod projecting beyond the end of the shaft and bearing upon the lever 83^c pivoted to a projection from the radial bar 9, the rod being normally held against such lever by means of a coil spring 83^d. The lower end of the lever carries a roller 83^e taking into a cam track upon the upper face of the cam plate 20, this cam track being so shaped as to, at different times, hold the clutch block intermediate of the gears 80 and 80^a or in engagement with one or the other of them. 10 The beveled pinion 78^a upon the horizontal shaft 78 is mutilated, that is to say has the teeth upon a portion or its periphery cut-away, whereby when such mutilated portion of the pinion comes into the line of centers 20 the driving effect of the shaft 78 upon the marverer carrying-frame 76 will be lost, but at other times the rotation of the shaft 78 will cause a movement of the marverer frame around its horizontal 25 pivot. A second wheel 84 is formed upon the horizontal shaft 78 and either meshes or frictionally drives a corresponding wheel 84^a formed upon the inner end of the marverer shaft. 30 The operation of a machine such as that heretofore described is as follows:—

The rotation of the head 5 around the central standard causes movements of the various parts driven thereby, and at some 35 interval of such rotation (preferably immediately after a gathering has been effected by the blowpipe or immediately after a glass-working spindle having an unformed gather of glass thereon is inserted in the machine), the marvering shaft 75 will be erect, and the glass-working spindle will be projected from the head at some angle to the radius on which the vertical pivot by which it is mounted is located, and at some 40 angle in respect to the horizontal. With the parts of the unit under consideration in this position, the mutilated portion of the pinion 78^a of such unit is at the line of centers and the clutch block 82 is intermediate of the two gears 80 and 80^a, being held in this position by its actuating cam rim. The continued rotation of the head will now cause the lever 83^c to enter such 45 part of the cam run as will throw the clutch block to lock the gear 80 to the horizontal shaft 78. This results in a rotation of the horizontal shaft in such direction as will cause the toothed portion of the beveled pinion 78^a to engage the beveled gearing 76^a upon the marverer frame to cause the marverer frame to descend to the position shown in full lines in Figure 2. After the descent of the marverer, the mutilated portion of the pinion 78 will again come into 50 the line of centers, and the continued rotation

of the horizontal shaft will no longer affect the position of the marvering frame. Simultaneously with these movements of the marverer frame, the glass-carrying spindle has been swung upon its horizontal pivot to place it in the plane of the marverer, and the end thereof having the glass thereon has been raised (if it was not already in this position) so that the gather is in position to enter the mouth 74^c of the 55 spiral of the marverer, when the latter has been lowered to its limit (see Fig. 3), it maintaining a fixed position during the marvering.

The lowering of the marverer brings the 80 wheels 84 and 84^a into engagement with each other, and results in a rotation of the marverer shaft and of the marverer, which, combined with the rotation of the glass-carrying spindle upon its longitudinal axis 85 results in the formation of the gatherer. The direction of rotation of the spindle is such that the gather rolls, instead of slides, along the interior of the spiral wall 74 of the marverer as the latter is rotated, 90 and due to the shape of such wall, which at each point is inclined to the direction of rotary movement of that point of the wall, the portions thereof which are brought successively in contact with the 95 gather, are successively closer to the axial line of the glass-carrying spindle, (which is held stationary, except for its rotation at this time) the solid mass of glass forming the gather will have all portions of its 100 circumferential walls brought into contact with the inner face of the spiral wall 74^c, whereby it will be rendered homogeneous, be given a surface chill, and will be reduced to a definite and predetermined size 105 and shape. After the marverer has been rotated through a predetermined arc around the axis formed by its shaft 74, the continued movement of the head 5 around the standard 2 will cause the lever 83^c to engage a portion of its actuating cam run 110 whereby the engagement of the clutch block will be shifted from the gear 80 to the gear 80^a, resulting in a reversal of the direction of driving of the horizontal shaft, and a 115 corresponding reversal in the direction of rotation of the marverer, carrying the latter back to the position illustrated in Figure 3. In this reversal of the rotation of the marverer, the spiral wall thereof will 120 move away from the marvered gather, so that the latter will not be rubbed during the time and during this period the mutilated portion of the pinion 78^a is in the line of centers, but at the termination thereof 125 the teeth upon the mutilated pinion again engage the beveled gear 76^a upon the marverer frame and swing the latter upon its horizontal pivot to restore the marverer to its initial position, after which the lever 83^c 130

engages a portion of the cam run 83^c, and disengages the clutch block 82 from the gear 80^a and centers it between it and the gear 80, thus arresting the rotation of the horizontal shaft 78. The glass carrying spindle is now given, by its actuating mechanism, movements necessary to swing the marvered gather and to position the spindle between the blowing and molding mechanisms.

10 In the above I described a complete and highly organized embodiment of my invention, but it will be seen that my invention, in so far as it relates purely to marvering mechanism, embodies in its broader aspects, only a support for a glass-working spindle, with means for properly rotating the spindle, and a rotating marverer, the face of which is so shaped that it is inclined to its line of travel, whereby upon its rotation the points thereof, which are successively in contact with the glass, are successively closer to the axis of the spindle.

20 Having thus described my invention, what I claim is:—

25 1. In a glass-blowing machine, the combination with a traveling marverer, the face of the said marverer being inclined to its line of travel and means for bringing a mass of plastic glass into proximity to the line of travel of the said marverer, substantially as described.

30 2. In a glass-working machine, the combination with a traveling marverer, of means for supporting a glass-carrying spindle in proximity thereto and means for varying the distance between the axis of the spindle and the marvering face.

35 3. In a glass-working machine, the combination with a support for a glass-carrying spindle, of a rotating marverer, successive points of which are brought into contact with the glass on the rotation of the marverer, which points are successively closer to the axis of the spindle, and means for rotating the spindle.

40 4. In a glass-working machine, the combination with a support for a glass-carrying spindle, of a rotating marverer whose marvering face is formed as a spiral around its axis of rotation, and means for rotating the spindle.

45 5. In a glass-working machine, the combination with a support for a glass-carrying spindle, of a rotating marverer, successive points of which are brought into contact with the glass on the rotation of the marverer, which points are successively

closer to the axis of the spindle, and means for rotating the spindle in such direction that the glass is rolled along the surface of 60

65 the marverer.

6. In a glass-working machine, the combination with a support for a glass-carrying spindle, of a rotating marverer, successive points of which are brought into contact 65 with the glass by the rotation of the marverer, which points are successively closer to the axis of the spindle, and means for rotating the spindle in such direction that the glass is rolled along the surface of the 70 marverer, and means for positioning the spindle in respect to the marverer, and subsequently positioning it in co-operative relation to a blow-mold.

7. In a glass-working machine, the combination with a carrier for a solid mass of glass, of a support for the carrier, a rotating marverer, and means for rotating the carrier to roll the glass thereon on this face of the marverer and means for rotating the 80 marverer.

8. In a glass-working machine, the combination with a carrier for a solid mass of glass, and a support for the carrier, of a rotating marverer whose marvering face is 85 formed as a spiral around its axis of rotation, and means for rotating the carrier in such a direction that glass is rolled along the surface of the marverer.

9. In a glass-working machine, the combination with a carrier for a solid mass of glass, of a rotating marverer whose working face is the inner surface of a spiral wall formed around its axis of rotation, means for reversely rotating the marverer and for 90 temporarily arresting it with the mouth of its spiral in position to receive the mass of glass, and means for rotating the spindle in such a direction that the glass is rolled along the surface of the marverer. 100

10. In a machine of the class described, the combination with a glass-working spindle adapted to carry a solid mass of glass, of a marvering part, means for moving the spindle to position the glass thereon 105 adjacent to the marvering part, and means for moving the marvering part in respect to the mass of glass, the face of the marvering part being inclined to the line of movement of such part. 110

In testimony whereof I have signed my name.

BENJAMIN DAY CHAMBERLIN.
